ERNEST EUGENE BISSETT, OF VANCOUVER, BRITISH COLUMBIA, CANADA.

CARGO-BUCKET-OPERATING DEVICE.

1,225,215.

Specification of Letters Patent.

Patented May 8, 1917.

Application filed October 18, 1915. Serial No. 56,509.

To all whom it may concern:

Be it known that I, ERNEST E. BISSETT, a citizen of the Dominion of Canada, residing at Vancouver, in the Province of British Columbia, Canada, have invented certain new and useful Improvements in Cargo-Bucket-Operating Devices, of which the following is a specification.

This invention relates to a device designed 10 to enable a clam shell bucket to be operated to lift, transfer and deposit its load by lines suspended from two derricks, one immediately over the head from which the load is to be lifted, and the other over the place of deposit, one line being connected to the suspension bail of the bucket, and the other to the mechanism by which the two halves of the bucket are drawn together to inclose and sustain the load.

20 Although specifically designed for this object the same device may be utilized for operating the release of any cargo bucket so suspended from two derricks that it may be traversed between them.

25 In loading and unloading ships by means of cargo buckets many disadvantages are attendant the use of a laterally swinging derrick, and wherever possible two derricks are used in the manner described, but heretofore 30 difficulty has been experienced in operating a clam shell bucket without the use of four lines, two for the suspension and transfer of the bucket, when closed, between the two derricks and two for the release of the buckets, one of each being taken over the head of each derrick.

The difficulty of operating the bucket with 35 two lines only is due to the fact that while the bucket will automatically hang open 40 when suspended over the heap from which the load is to be lifted, if the other line is tightened to close the bucket, the tension on that line draws the bucket toward the other derrick before the closing can be effected; 45 or conversely, if the bucket is suspended closed from the release line over the place of deposit that line cannot be slackened to effect the deposit of the load without the bucket swinging on the other line back toward the other derrick.

50 In the device, which is the subject of this application, this difficulty is overcome by providing a means for holding the bucket in the closed position while it is being transferred to the place of deposit and for holding it in the open position while transferring

it to the place from which the load is to be lifted.

The invention is particularly described in the following specification, reference being 50 made to the drawings by which it is accompanied, in which:

Figure 1 shows the bucket as suspended over the heap from which the load is to be lifted, the dot and dash lines indicating the 55 movement by which the closing of the bucket is effected, and

Fig. 2, its position over the place of deposit, the dot and dash lines indicating the 70 action of the device by which release of the closing means is effected.

In these drawings 2 represents each half of a clam shell bucket, each outer corner of which is pivotally connected at 3 by a suspension rod 4 to a suspension block 5. 75 To this suspension block 5 a line 6 is connected over the head of a derrick whose point of suspension 6^a, which is immediately over the place of deposit 7, to the drum of the winch by which that line is operated. 80

The bucket operating line 8 passes from a separate winch over the head of another derrick, whose point of suspension 8^a is over the place 9 from which the load is to be lifted, and the line passes through the suspension block 5, thence down around the pulley 10^a on the spindle 10, up around the pulley 5^a in the block 5, down around 10^a and back up to the block 5 to which it is connected at 5^b, so that as tension is imposed on 90 that line 8 the bucket will be closed and if the line is relaxed the buckets will of their own weight fall open.

Without further provision, if the bucket is 95 hanging on the line 6 from the derrick over the place of deposit 7 and the line 8 is slack, the two halves of the bucket will fall open of their own weight, and if suspended on the line 8 from the other derrick over the place from which the load is to be lifted and the 100 line 6 is slack, the bucket will hang closed.

The device, which is the subject of this application, is designed to enable the bucket to hang open not only when it is 105 hanging on the line 6 over the place of deposit 7, where it must be open to drop its load, but over the place 9 from which the load is to be lifted to enable it to inclose a load; and when the bucket is closed on its load, which is its natural position when 110 hanging over the place 9 from which the load is to be lifted on the line 8, it must re-

main closed while being transferred to the place of deposit, and where the closing means being relaxed it will naturally fall open to deposit its load.

5 These objects are attained by passing both lines 6 and 8 before connection to the bucket through a linking block 11 having two small roller sheaves over which the lines may run freely. This linking block is not secured to either line. It merely brings the lines together and from it they run alongside one another to their connection to the bucket. Between this linking block 11 and connection to the lines 6 and 8 to the bucket a 15 tumbling rod 16 is pivotally connected at 14 and 15 to each line.

This tumbling rod 16 will naturally tend to hang from the line which effected the change in the condition of the bucket, that is, the end 14 of the rod, which is connected to the line 6, will be uppermost when the bucket has been opened to deposit its load and the end 15 connected to the line 8 will be uppermost when the bucket is hanging 25 from the line 8 which has just effected the closing of the bucket. If the rod 16 is maintained in its position alongside the line which effected the change in the condition of the bucket, the bucket may be suspended 30 from either line but any tension on the line to which the lower end of the tumbling rod is connected cannot be communicated by that line to the bucket but will pass endwise through the rod to the other line.

35 To retain the tumbling rod 16 alongside the line which effected the change in the condition of the bucket, a shackle 17 is endwise movable along the tumbling rod 16 and is pin-connected at 20 to shackles 18 and 19 40 movable along the suspension lines 6 and 8, below the connection of the tumbling rod thereto, and these shackles may have small roller wheels mounted on them to facilitate movement along the lines when inversion of 45 the rod is required.

The end 14, which is connected to the line 6, suspension from which line effects the opening of the bucket, being uppermost, the shackles 17, 18, 19 will be at the end 14 of 50 the rod 16 and will hold that end of the rod alongside the taut line 6, so that the bucket may be suspended from either line 6 or 8 without effecting any change in the condition of the bucket to close it, so long as 55 any tension is maintained on the line 6; but if the line 6 is slackened, the tumbling rod 16 will invert, that is, the end 14 will fall below the end 15 and the weight of the bucket will be sustained entirely by the line 60 8 and the bucket will therefore be closed, and the shackles 17, 18, 19, will accommodate themselves to the inversion of the rod and will fall to the lower end 14 of it to retain it alongside the line 8, in which position the 65 weight of the bucket may be suspended from

either line 6 or 8 without change in the closed position of the bucket, so long as any tension is maintained on the line 8, but slackening of the line 8 will again permit the tumbling rod to invert and the weight of the 70 bucket will be imposed on the line 6 and will fall open.

It must be noted that the bucket after having been opened to deposit its load is suspended mainly from the line 6 and that it requires to be transferred in that open position to the place from which the load is to be lifted, where the weight of the bucket is mainly suspended on the line 8 and would be closed but for the action of the tumbling rod 80 which prevents that closing tension of the line 8 being transmitted to the bucket closing mechanism; but the closing can be effected by slackening the line 6 and permitting the tumbling rod 16 to invert. Conversely, the 85 closed bucket may be transferred to the place of deposit where again the greater tension being on the line 6 the bucket would naturally tend to open but for the fact that the tension on the line 6 is transmitted endwise 90 through the tumbling rod to the line 8, so that the bucket is suspended on that line, and is maintained closed.

When it is required to open the bucket and deposit the load, the line 8 is slackened 95 to permit the tumbling rod 16 to invert, and the weight of the bucket and its load being then maintained entirely on the line 8 the bucket will fall open to deposit its load.

The bucket having dropped its load is 100 transferred to the place of loading, by winding in the line 8 and paying out correspondingly the line 6 without allowing that line 6 to be slack. On reaching the heap from which the load is to be lifted the open bucket 105 is lowered upon the heap and the line 6 is slackened, the tumbling rod 16 again inverts, and as the line 8 is wound in the bucket is first closed to inclose its load from the heap and thereafter is lifted and swung across to 110 the place of deposit by winding in the line 6 and paying out the line 8 without allowing the line 8 to be slack until the bucket arrives at the place of deposit when on slackening out the line 8 the tumbling rod again inverts 115 and the bucket falls open to deposit the load.

By this simple and inexpensive provision a clam shell bucket may be operated by two lines between the heads of two derricks, one over the place of loading and the other over 120 the place of deposit, and the same requires the use of no further attendance than that of the man operating the winches.

Although specifically designed for the operation of a cargo bucket of the clam shell 125 class, the same device may be modified to operate an ordinary gravity-tilting cargo bucket, the inversion of a short tumbling rod 16 serving to effect release of the bucket. Transference and deposit of the load being 130

effected by the operation of the hoisting lines alone the attendance of a man to release the tumbling latch is saved.

Having now particularly described my invention, I hereby declare that what I claim as new and desire to be protected in by Letters Patent, is:

1. The combination with a cargo bucket, means for suspending two hoisting lines at different points of location, the first point of location being over the place from which the load is to be lifted and the other over the place at which the load is to be discharged, said bucket comprising a suspension block, and bucket elements suspended therefrom and adapted to open and close, one of said hoisting lines being connected directly to said suspension block, the other of said hoisting lines coöperating with the bucket elements for opening and closing the same, and a device connecting said hoisting lines adjacent to the bucket whereby when said device is in one position, the bucket will hang closed beneath one of said points of suspension, and when said device is in another position said bucket will hang open beneath the other of said points of suspension, said device being operable by slackening one or the other of said hoisting lines according to the location of the bucket.

2. The combination with a cargo bucket, two hoisting lines, one suspended over the place from which the load is to be lifted and the other suspended over the place at which the load is to be deposited, means operative by the hoisting lines for sustaining the bucket in the open position over the place from which the load is to be lifted and for sustaining it in the closed position over the place of deposit, comprising a link for holding the lines substantially parallel to one another adjacent to their place of connection to the bucket, and a tumbling rod one end of which is pivotally connected

to each line between said link and the bucket, and releasable means for holding the lower end of the tumbling rod adjacent the lines.

3. The combination with a cargo bucket, two hoisting lines and means for suspending said lines at two different locations, a linking block through which both lines pass before being connected to the bucket, a tumbling lever, one end of which is connected to each line between the linking block and the places of connection of the lines with the bucket, and movable means on both lines and on the tumbling rod, for holding the lower end of the lever adjacent to said lines.

4. The combination with a clam shell bucket, of two hoisting lines for suspending said bucket, means over the place where the load is to be lifted for sustaining one of said lines and means over the device where the load is to be deposited for sustaining the other of said lines, a linking block through which both lines are freely movable, a tumbling rod, one end of which is pivotally connected to each line between the linking block and the bucket, and connecting linking shackles endwise movable on the tumbling rod and on the lines for connecting the lower end of the tumbling rod to said lines.

5. The combination with a cargo bucket, two hoisting lines from which said bucket is suspended, means for suspending one of said lines at one place and the other of said lines at another place, means whereby the bucket may be sustained over the place from which the load is to be lifted on one line and on a part of the other line and for sustaining the bucket over the place of deposit on the other line and on a part of the first line, and means operated by the hoisting lines for transferring the weight of the bucket from one line to the other in each case.

In testimony whereof I affix my signature.
ERNEST EUGENE BISSETT.
